DROPOUT FUSE CONSTRUCTION HAVING A COMBINED UPPER LATCH AND CONTACT
 Frederick E. Reiber and Gene L. Miller, Bloomington, and Robert J. Lawrence, Ellettsville, Ind., assignors to Westinghouse Electric Corporation, East Pittsburgh, Pa., a corporation of Pennsylvania

Filed Apr. 17, 1961, Ser. No. 103,634

5 Claims. (Cl. 200—114)

This invention relates, in general, to electric circuit interrupters of the dropout fuse type, and more specifically, to the contact mechanism therein.

In the past, the fixed contact of a fuse cutout of one type has required the presence of a separate latch mechanism for engaging the fuse holder contact to maintain the contact in engagement with the fixed contact during normal circuit operation, as in copending application Serial No. 91,219, filed February 23, 1961, by A. J. Fink et al., which issued June 23, 1964, as U.S. Patent No. 3,138,681. In other prior devices where the contacts are of the gripping finger type, the need for a separate latch is eliminated, but a separate spring mechanism is required to bias the fuse tube holder and contact in the dropout direction to effect a disengagement between the fuse holder contact and the fingers of the fixed contact, as for example in Patent No. 2,938,093.

It is an object of this invention to provide a fixed contact mechanism for a dropout fuse cutout, which contact eliminates the necessity of a separate latch means and also eliminates the necessity for separate biasing means for the fuse tube.

More specifically, it is an object of this invention to shape the fingers of a fixed contact device for a fuse cutout in a unique manner to provide for latching the fuse holder contact between the fingers during normal circuit operation and to also provide for biasing the fuse holder toward the dropout position.

Further objects and advantages will readily become apparent to those skilled in the art upon reading the following specification, taken in conjunction with the drawings, in which:

FIGURE 1 illustrates a generally vertical sectional view taken through an enclosed fuse cutout, the contacts of the present invention being shown in side elevational view, and the fuse cutout being illustrated in its operative condition for carrying line current therethrough;

FIG. 2 is an enlarged top plan view of the fixed contacts shown in FIG. 1 and embodying this invention; and

FIG. 3 is an enlarged side elevational view of the contact backer spring for the contacts of FIG. 2.

Referring to the drawings, there is shown a fuse cutout generally indicated by the reference numeral 1 and which is substantially identical to the fuse cutout disclosed in the copending application Serial No. 91,219, filed February 23, 1961, now Patent No. 3,138,681, with exceptions hereinafter described as constituting the present invention.

The fuse cutout 1 includes an insulating housing 2, which may be formed of any desired insulating material, such as porcelain.

The porcelain housing or box 2 comprises a rear wall 3, a top wall 4, and oppositely disposed side walls 5 (only one shown). It will be noted, therefore, that the front and bottom of the porcelain box 2 are open. The rear wall 3 is provided with an inwardly extending protuberance 7 forming with an integral flange 8 a transverse baffle intermediate the ends of the insulating casing 2. The protuberance 7, as shown, is provided with a cavity 11 opening to the outer side of rear wall 3 and adapted to receive one end of a mounting bracket 12 for supporting the casing 2, for example, from a cross-arm hanger.

2

As shown in FIG. 1, the mounting bracket 12 may be apertured, as at 15, to provide better securement within a resilient cement 16 contained within the cavity 11 and may be of a type described in the hereinbefore mentioned 5 copending application. The cavity 11 may also be sanded during fabrication of the fuse casing 2 for additional strength of securement.

Within insulating casing 2 there is provided upper and lower contact assemblies 17 and 18, respectively, secured 10 within cavities 21, 22, respectively, provided in the inner surface of rear wall 3 of the casing 2. The upper contact assembly 17 includes a forwardly projecting U-shaped contact strip 150 (FIG. 2) of any desired conducting material, such, for example, as copper or the like, with a resilient U-shaped backing strip 151. Preferably, the backing strip 151 is formed from a suitable resilient material, such as Phosphor bronze.

The U-shaped contact strip 150 comprises a bight portion or base 152, having integrally fixed at the ends thereof 20 a pair of leg members 153 extending outwardly in laterally opposed relationship with respect to each other. Each of the leg members 153 is doubly recurved along its length resulting in two spaced points 154 and 155 on each leg, which points are bent inwardly toward each other to comprise an inner stop 154, 154 and an outer stop 155, 155, respectively. The inner stop inhibits inward movement of the upper end of fuse element 33 while the outer stop inhibits outward movement of the fuse element 33 after the element has been moved inwardly of the outer stop. The intermediate portions 156 of each leg, between 25 the points 154 and 155 is curved away from the other so as to congruently mate with opposite sides of the upper end of the previously described fuse element 33, thus providing sufficient electrical connection between the contact 150 and the fuse element 33. As best seen in FIG. 35 2, the intermediate portions 156 are canted with respect to the vertical plane of the strip 152 so as to flare laterally outwardly and downwardly.

The outer end portions 157 of the leg members 153 are bent laterally away from each other to serve as a guide for the inwardly moving upper end of fuse element 33.

The backer 151 is comprised of a bight portion 158 and integral leg portions 159 shaped to congruently mate with legs 153 of contact 150 to provide resiliency to the contact. If the contacts are constructed of material having sufficient inherent resiliency, the backer may be dispensed with.

The foregoing structural characteristics of the contacts 150 provide several advantages. The basic U-shape of the contact 150 provides firmer contact during passage of current which provides magnetic flux holding the contact legs 153 together to minimize burning. The recurved nature of the legs 153 provide integral latch means for holding the fuse element 33 securely in place during normal operation, thus eliminating separate latch means. The canted or flared nature of the intermediate portion 156 of legs 153 redirect the previously described holding force to a resultant downward force against the fuse element 33 and axially of the fuse element to urge the hereinbefore described toggle mechanism to the toggle release position upon fusing of the fuse link to effect rapid opening of the fuse cutout in the manner hereinafter described in detail.

The lower contact assembly 18 includes a U-shaped contact strip 31 and a resilient U-shaped backing strip 32, the latter being formed from a resilient metallic material, such as phosphorus bronze. The intermediate portions of the contact legs converge and the end portions diverge to form a sloped surface suitable for engaging and stopping the movable contacts as fully described in detail in the copending application previously mentioned. The contact backer 32 is curved to respectively mate with the

intermediate and outer portions of the contact strip 31.

The support terminal 38 is suitably apertured for receiving studs 43 anchoring the stationary contacts 150 and backer 151 to the end of support 38.

The contact and backing strips of both the contact assemblies 17, 18 are mounted in position by means of an angle-shaped support bracket 40, a pair of rivets 41 being employed for the connection.

It will be observed that contact strip 150 has a downwardly extending end portion 44 which is disposed within box-shaped support terminal 38. Lower contact strip 31 likewise has a depending portion 45, which is similarly positioned. A pair of terminal screws 46 are threaded of each support terminal 38 and have contacting shoe clamps 48 rotatably secured thereto at the inner ends thereof.

As a result of the foregoing construction, the line conductor and also the load conductor, not shown, may be threaded into the side lead opening (not shown) of casting 2 and forced under pressure by the contacting shoe clamps 48 directly against the curved depending receptive portions 44, 45 of contact strips 150, 31, respectively. As a result, no unnecessary joints are provided in the current path extending through the fuse cutout 1.

It will be noted that the angled support brackets 40 have an angled portion 50, which is cemented into the cavities 21, 22 of the casing 2. Any suitable cement, such as high-strength mineral lead cement 51, may be employed.

With reference to FIG. 1, it will be noted that the porcelain fuse housing 2 is provided with threaded metallic pivot pins 53 extending through opposite sides of the housing 2 and retained by cooperating insulating nuts (not shown). The pins 53 (only one shown) form inwardly extending trunnions to removably pivotally support a fuse-holder door, generally designated by the reference numeral 57.

Preferably the fuse-holder door 57 is formed of a suitable insulating material, such, for example, as porcelain, a synthetic resin, or the like. The molded door 57 is provided with an apertured handle 58, which may be manipulated by a switchstick at a distance, or by hand for the lower voltages. The openings 59 in the handle 58 may be grasped by the hand of the lineman, but preferably, for reasons of safety, switchstick operation is desirable with the prong of the switchstick inserted within the opening 59 to effect closing and opening rotative motion of the fuse-holder door 57 about the pivot pins 53, as herein-after more fully described.

Fuse-holder door 57 comprises a door panel 60 having a rearwardly integral apertured mounting projection 61. In addition, door 57 has an intermediately disposed recess 63 for the accommodation of a sponge rubber, washer-shaped barrier member 64, and rivets 65 molded with the door. Also fuse-holder door 57 has a transverse integral flange 66 with an arcuate cutout portion, not shown, for accommodating a tubular fuse-holder, generally designated by the reference numeral 68. The lower portion of the molded door 57 is provided with a pair of trunnion receiving flared notches 71 (only one shown) for receiving the pivot pins 53 on casing 2. The top of the door 57 is provided with a top inwardly extending flange portion 73.

The tubular fuse-holder 68 comprises a top knurled contact cap 74, which is threaded into a fuse ferrule 75, the latter, in turn, being threaded upon the upper threaded end of a fuse tube 76 and fixedly cemented thereto.

It will be noted that the contact cap nut 74 of fusible device 33 is tapered from the base inwardly toward the top to fit in mating relation with the previously described flared intermediate portions 156 of contacts 150. In addition, the cap has a cylindrical recess (not shown), which is not utilized in this invention but engaged by the latching portion of a spring latch shown in copending application Serial No. 91,219.

The mounting aperture 78 of mounting projection 61

has a shoulder portion 81, which limits the downward movement of fuse ferrule 75 when tubular fuse holder 68 is inserted into mounting aperture 78.

As well known by those skilled in the art, a button-type fuse-link assembly, generally designated by the reference numeral 82, is inserted into the top of tubular fuse-holder 68 following removal of knurled contact cap 74. The buttonhead of the link assembly is clamped between the bottom of the contact cap 74 and a threaded plug, not shown, threaded interiorly within fuse ferrule 75. The fuse link may be of the type described in United States Patent 2,343,723, issued March 7, 1944, to James M. Wallace and assigned to the same assignee as the present application.

The lower cable or tail 83 of the fuse-link assembly 82 extends through the lower open end of the bore provided within fuse tube 76 and is clamped between a freely rotatable washer 84 of a terminal clamp 85 and the knurled side (not shown) of a pivotally mounted support link, or door hinge 87. In the intact, or unblown condition of the fuse link 82, a toggle means 88 is maintained in its set or unbroken position. However, when fuse link 82 fuses upon overload or fault-current conditions, the cable 83 is released, and the toggle means 88 breaks, or collapses, to permit lowering and outward movement of the fuse-holder door 57 and consequent unlatching of contact cap 74 from the flared portions 156 of contacts 150. The entire fuse-holder door 57 then drops downwardly to the dropout indicating position shown by dot-dash lines in FIG. 1.

Preferably, the fuse tube 76 is composite in construction having an inner gas-evolving liner of fiber, or like material, and an outer surrounding casing of insulating material preferably glass reinforced epoxy. By using a strong outer layer, greater bursting strength is achieved and a thinner outer wall is permitted, thus allowing a thicker layer of fiber. The thicker fiber provides a greater ability to withstand erosion due to arcing. The evolution of the gas from the fiber liner during the drawing of the arc within the fuse-tube bore will assist an arc extinction, the evolved gas being expelled downwardly through the lower open end of the fuse tube 76 with expulsive action. This expulsive action will, of course, assist in the ejection of the lower remnant of the fuse link out of the fuse tube.

It will be noted that the rivets 65, molded with the door 57, are employed to secure fixedly in place a latch bracket or catch 93. The rivets 65 extend through appropriately positioned holes of latch bracket 93 and have their inner ends swaged, or peened over to rigidly mount the latch bracket 93 on the door 57. Preferably, a resilient rubber pad 95 of generally rectangular configuration is disposed between the inner side of the door panel 60 at the bottom of a recess 96, and the bight portion of latch bracket 93 for minimizing shock imposed upon the molded door 57 during operation of the cutout. The pad 95 is, of course, provided with apertures to accommodate the pair of rivets 65.

The legs 98 of latch bracket 93 have three threaded holes provided in the sides 98 of the latch bracket 93. The upper two holes receive the inner ends of pivot screws 102 (FIG. 1), the shank portions of which pass with clearance through suitable pivot holes of supporting link 87. The inner extremities of the two pivot screws 102 extend into bored openings, or recesses provided in the side walls of fuse tube 76. These recesses, not shown, do not, however, extend to the inner surface of the bore extending through fuse tube 76. Thus, the inner ends of the pivot screws 102 serve to fixedly attach the fuse-holder 68, including the fuse tube 76, to the door 57. By unscrewing the pivot screws 102, however, the supporting link 87 may readily be removed from the latch bracket 93, or door 57, and the freed fuse tube 76 may be removed from door 57 by upward withdrawal movement through mounting aperture 78 of projection 61. When

desired, a new fuse tube 76 may be substituted in this manner for an old fuse tube 76.

The toggle means 88 comprises the fuse-holder 68 as one leg of the toggle, and the supporting link 87 as the other leg of the toggle. The supporting link 87 is received upon the pivot pins 53 supported upon the side walls 5 and 6 of the casing 2. The link 87 may be readily attached and detached with respect to supporting pivots 53 by movement of the link 87 to cause entrance or exit of supporting pins 53 into slots in the supporting link 87 which slots line up with the notches 71 provided in opposite side edges of door panel 60 to permit the link 87, when assembled with the fuse holder 68 and door 57, to be engaged or disengaged with pivot pins 53. The notches 71 in the door panel 60 are, as shown, flared outwardly to facilitate easy entrance of pivot pins 53 into the notches 71 and slots in the supporting link 87.

The lower threaded hole or link 87 accommodates a converting screw 106, which passes with clearance through a hole in link 87, and thereby adapts the fuse cutout 1 for non-dropout operation. Removal of this converting screw 106, which is mounted in place at the factory, provides dropout operation, since the toggle means 88 is then free to collapse. If the converting screw 106 is maintained in position, as supplied from the factory, the supporting link 87 is rigid with latch bracket 93 and door 57, and the toggle means 88 is rendered inoperable.

It will be noted that a spring latch, generally designated by the reference numeral 108, is mounted at the lower end of the supporting link 87 and includes a sleeve 109. This spring latch 108 described in detail in copending application Serial No. 91,219 is mounted upon the door-hinge assembly, and permits only a correct and controlled force upon the fuse link and aids the fuse cutout 1 in clearing faults. It also serves as a fuse-link flipper indicating a blown fuse when the fuse cutout 1 is adjusted for non-dropout operation.

It will be noted that supporting link 87 has a contacting portion 116 for accommodating the fuse tube 76 in the closed-circuit position of the device, as shown in FIG. 1. The contacting portion 116 has flared ends 114 for mating engagement with outer end portions of the lower contact strip 31 of lower contact assembly 18 with a wiping and pressurual engagement. The upper contact cap nut 74 likewise engages the contact plate legs 153 with pressurual engagement. Thus, adequate contact pressure is provided in the latched closed position of the fusible device 1. This contact pressure tends to cause breaking or collapse of the toggle means 88, which is resisted by the fuse-link assembly maintaining the spring latch in its locking position, as shown in FIG. 1. The contact pressure provided between the resilient U-shaped lower contacts 31 and the movable contacts 116 on support link 87 in a direction perpendicular to the fuse tube serves to provide a force urging the fuse tube 68 and support link 87 outwardly of the box 2 to assist in collapsing the previously described toggle mechanism when the fuse link 83 fuses.

When the line conditions are such as to permit excessive current to flow through the cutout 1 by way of contact assemblies 17, 18 and fuse-link assembly 82, this excessive current will cause fusing of the fusible element disposed within fuse tube 76 and associated with fuse-link assembly 82. The fusing of the fusible element will release the spring-biased latching device 108 causing it to operate to effect withdrawal of the lower remnant of fuse-link assembly 82 downwardly out of the lower open end of the fuse tube 76. Arc lengthening is thereby augmented, and an indication of a blown fuse condition is obtained. Simultaneously with the withdrawing motion of the fuse-link flipper 108, there occurs unlatching of the cutout toggle mechanism 88. Preferably, arc extinction occurs within fuse tube 76 prior to breaking or collapse of toggle means 88 to prevent any arcing at the contacts.

The force exerted by the lower back-up spring 32 acts

to break the toggle means 88 and effect counterclockwise rotation of supporting link 87 about its pivot axis 53, thus effecting outward and dropping movement of the fuse-holder door 57 upon collapse of the toggle means 88.

5 At the same time, the upper contacts 150 will exert a downward force on the contact 74 to assist in breaking the toggle 88. The tapered contact 74 will be urged downwardly away from the canted contact portions 156. The fuse-holder 57 will swing in a counterclockwise direction about the pivot pins 53 to the dot-dash open position of FIG. 3.

While there has been shown and described a particular embodiment of the invention, it will be obvious to those skilled in the art that changes and modifications may be made without departing from the invention, and that it is intended by the appended claims to cover all such changes and modifications as fall within the true spirit and scope of the invention.

We claim as our invention:

20 1. A fuse cutout comprising upper and lower stationary contacts spaced apart from one another, a tubular fuse holder having a contact formed at the extreme end portion thereof disposed to engage said upper contact, a fixed support pivot, a link member pivotally connecting said fuse holder to said fixed support pivot and forming therewith a collapsible toggle means, a fuse link carried by said fuse holder and normally cooperating with said fuse holder and said link member to prevent the collapse of said toggle means, said upper stationary contact comprising a pair of resilient contact strip members extending outwardly from a common plane and having integral intermediate portions the integral intermediate portions of said contact members being laterally spaced apart and generally curved to prevent lateral movement of one end of said fuse holder in either direction, said intermediate portions being flared outwardly in a direction toward said lower contact to apply an axial force to said fuse holder in the latter direction to urge the contact of said fuse holder out of engagement with said contact members when said fuse fuses, the shape of said contact at the extreme end portion of said fuse holder being tapered adapted to substantially mate with the intermediate portions of said contact members with a substantial portion of the contact on said fuse holder engaging said contact strip members.

45 2. A fuse cutout comprising upper and lower stationary contacts spaced apart from one another, a tubular fuse holder having a contact formed at the extreme end portion thereof disposed to engage said upper contact, a fixed support pivot, a link member pivotally connecting said fuse holder to said fixed support pivot and forming therewith a collapsible toggle means, a fuse link carried by said fuse holder and normally cooperating with said fuse holder and said link member to prevent the collapse of said toggle means, said upper stationary contact comprising a pair of resilient contact strip members extending outwardly from a common plane and having integral intermediate portions, the integral intermediate portions of said contact members being laterally spaced apart and generally curved to prevent lateral movement of one end of said fuse holder, said intermediate portions being flared outwardly in a direction toward said lower contact to apply an axial force to said fuse holder in the latter direction to urge the contact of said fuse holder out of engagement with said contact members when said fuse fuses, the shape of said contact at one end of said fuse holder being frusto-conical and adapted to substantially mate with the intermediate portions of said contact members when said fuse fuses, the shape of said contact at the extreme end portion of said fuse holder being tapered adapted to substantially mate with the intermediate portions of said contact members with a substantial portion of the contact on said fuse holder engaging said contact strip members.

70 3. A dropout fuse cutout, comprising: upper and lower

spaced apart line contacts; at least the upper contacts comprised of a pair of laterally opposed contact members extending outwardly from a common plane and diverging downwardly; a fuse link including an upper contact; a fuse holder mounting said link for motion inwardly between said members; said fuse holder including means operable when released to permit movement of said contact of said fuse link downwardly for effecting release of the contact from said contact members, the extreme end portion of said fuse holder forming a contact terminal; said contact members each being shaped to provide integral means thereon for latching said contact terminal therebetween to prevent lateral movement of said contact terminal and being flared laterally outwardly and downwardly to apply a downward axial force to said fuse holder, said contact terminal of said fuse holder being tapered to fit in substantially mating relationship between said upper contact members with a substantial portion of said contact terminal engaging said contact members.

4. A dropout fuse cutout, comprising: upper and lower spaced line contacts; a fuse tube disposed to extend between said contacts, the extreme end portion of said fuse forming a contact terminal, a fuse link disposed in said fuse tube and having an upper contact thereon; a pivot fixed with respect to said contacts; collapsible linkage connecting said fuse tube to said pivot; said linkage forming a rigid link between said tube and pivot when held in a first position; said linkage collapsible to shorten the length between the tube and pivot; said fuse link connected to one of said contacts holding said linkage in said first position and fusible to permit collapse of said linkage; said upper line contacts comprising a pair of laterally opposed arms laterally curved to engage said contact terminal of said fuse tube and to prevent lateral movement of said fuse tube and vertically diverging to apply a downward force to said fuse tube and to assist in effecting release of said fuse link contact when said linkage collapses, said contact terminal of said fuse tube being tapered in shape to substantially mate with said pair of opposed arms with a substantial portion of said contact terminal engaging said opposed arms.

5. A dropout fuse cutout, comprising: a pair of upper and lower spaced line contacts; at least the upper line

contacts comprising a pair of relatively stationary laterally opposed contact members extending outwardly from a common plane, a movable member, said pair of contact members being adapted to engage one end of said movable member at opposite sides thereof when the movable member is moved inwardly between the contact members; said contact members including bent portions intermediate the ends thereof for preventing lateral movement in either direction of said movable member, 5 said contact members each extending downwardly in a relatively laterally diverging direction away from the other of said contact members to apply a downward axial force to said movable member; said movable member comprising a fuse holder means and fuse link means and 10 having an upper contact formed thereon at the extreme end portion of said fuse holder means and being operable about a pivot to move said upper contact inwardly between said pair of contact members; said fuse holder means including a linkage collapsible to move said fuse 15 link in a downward direction to effect release of said upper contact from said pair of contact members; said fuse link means normally holding said linkage in a non-collapsed position and fusible to permit collapse of said linkage; said upper contact having a tapered configuration 20 substantially complementary to that of the diverging portions of said pair of contact members with a substantial portion of the upper contact of said fuse holder means 25 engaging said contact members.
